Primary Examiner — Jennifer Rivard*Assistant Examiner* — Alison M Ofstun(74) *Attorney, Agent, or Firm* — Jonathan A. Bay(57) **CLAIM**

The ornamental design for a device for nasal cavity cleaning and application of essential oils, as shown and described.

DESCRIPTION

FIG. 1 is a perspective view of a device for nasal cavity cleaning and application of essential oils, showing my new design, shown in an environment of use;

FIG. 2 is a second perspective view thereof, shown in a second position and environment of use;

FIG. 3 is an enlarged perspective view thereof, shown with the environment removed;

FIG. 4 is a left side elevational view thereof, the right side being a mirror opposite image thereof;

FIG. 5 is a rear elevational view thereof;

FIG. 6 is a front elevational view thereof;

FIG. 7 is an enlarged top plan view thereof;

FIG. 8 is an enlarged bottom plan view thereof; and,

FIG. 9 is an enlarged cross-sectional view thereof, taken along line 9-9 in FIG. 6.

The article is shown with a symbolic break in its length. The appearance of any portion of the article between the break lines forms no part of the claimed design.

The broken lines in the drawing represent environmental subject matter that forms no part of the claimed design.
